UNITED STATES PATENT OFFICE.

EMERY M. HAMILTON, OF NEW YORK, N. Y.

TELEGRAPH-KEY.

SPECIFICATION forming part of Letters Patent No. 379,063, dated March 6, 1888.

Application filed August 29, 1887. Serial No. 248,122. (No model.)

To all whom it may concern:

Be it known that I, EMERY M. HAMILTON, of the city of New York, in the county and State of New York, have invented an Improvement in Telegraph-Keys, of which the following is a specification, reference being had to the accompanying drawings, forming part of the same, in which—

Figure 1 is a side elevation of a telegraph-key containing my invention. Fig. 2 is a plan of the same, and Fig. 3 is a plan or upper face view of the key-lever detached from its connection with the key.

My invention is an improvement upon the telegraph-key for which Letters Patent of the United States were granted to me dated December 26, 1882, and numbered 269,521; and it consists in the special devices herein described and claimed.

20 A is the frame or plate on which the working parts are mounted.

B is the key-lever. It is made in the form of a cross, as shown in the drawings, and may be cut out of sheet metal of suitable thickness. 25 The long arm a is provided with a contact-point, b, for making and breaking contact with the anvil c, insulated on the plate A.

d is the spring, located between the fulcrum of the lever and the said contact-point b, and 30 near the said fulcrum, for breaking the circuit by raising the said long end of the lever. The short end f of the lever carries the set screw g, for regulating the distance of vibration of the lever.

35 h h' are separate studs fixed in the plate A, on which the lever B is fulcrumed. Each is provided with an overhanging lip, i i', beveled to a knife-edge on the under side. Near the extremities of the cross-arms j j' of the lever 40 on their upper faces are made recesses k k', with inclined sides meeting at the bottom at an angle somewhat greater than the angle formed by the inclined sides of the lips i i', so

that the lips may rock in the recesses. The said lips and recesses are of corresponding 45 length, whereby the ends of the lips abutting against the end walls of the recesses prevent all lateral shifting of the lever, and thereby avoid any rubbing together of the contact-points. 50

When the lever is placed with the ends of its cross-arms under the overhanging lips i i' and the lips adjusted in the recesses h h', the spring d, together with either the contact-points or the set-screw g, maintains the lever 55 in place, and the separate lips i i' and recesses h h' constitute durable easily-operating fulcrum-joints that insure at all times a perfect make and break at the contact-points without any rubbing or shifting motion of one point on the 60 other—a motion which is very deleterious to the action of a telegraph-key.

Without departing from the spirit of the invention, the position of the described lips i i' on the studs p p' and the recesses k k' in the 65 cross-arms of the lever B may be reversed, the lips in the form of projections being formed on the lever and the recesses in the under face of overhanging projections on the studs.

What I claim as my invention, and desire to 70 secure by Letters Patent, is—

In a telegraph-key, the cruciform lever B, made of a single piece of metal and provided with a set screw, g, carried on the short arm f, and with a contact-point, b, carried on its 75 long arm a, and the spring d, located between the fulcrum of the lever and the said contact-point, the said lever being fulcrumed near the extremities of its cross-arms j j' on the separate studs h h' by the lips i i' and the recesses 80 k k', all constructed and combined to operate as and for the purpose described.

EMERY M. HAMILTON.
